UNITED STATES PATENT OFFICE.

JOHN C. BURKHOLDER, OF WEST END, NORTH CAROLINA, ASSIGNOR TO WESTERN ELECTRIC COMPANY, INCORPORATED, OF NEW YORK, N. Y., A CORPORATION OF NEW YORK.

SIGNALING SYSTEM.

Application filed January 5, 1922. Serial No. 527,097.

This invention relates to signaling systems and more particularly to a carrier current system.

In the operation of carrier current systems heretofore devised, it has been found that as the potentiometer inserted between the carrier wave source and the transmission line is adjusted to effect "gain" control by increasing or decreasing the potential impressed upon the grid or control element of an amplifier and thereby meet varying transmission characteristics due to changes in line or atmospheric conditions, the frequency of the carrier source is changed. The average change for the entire potentiometer range for frequencies between three and ten thousand cycles is about 125 cycles. This change in carrier frequency, is of course, undesirable as a variation of this magnitude reduces the channel spacing i. e., the frequency interval between carrier frequencies, and in most cases, causes considerable interference between channels; while it also limits the portion of the frequency spectrum available for signal purposes.

The present invention is directed to a circuit arrangement involving a resistance network, adapted to be used in place of the sending potentiometer, which functions to maintain the impedance between the oscillator and the transmission line substantially constant over the whole frequency range utilized for signal purposes. Closer spacing of the channels is therefore possible and impedance variations external to the oscillator circuit are prevented from reacting upon the oscillator to change its frequency, whether these variations are due to gain control adjustments, line disturbances, or other causes.

According to this invention, a resistance in series with the potentiometer resistance is included in the oscillating current output circuit of the oscillator and a pair of resistances which are of equal value are connected between the terminals of the potentiometer resistance and the adjustable contact associated with it. Thus each of the equal resistances is connected in parallel across one half of the potentiometer resistance through its associated adjustable contact. As this contact is adjusted to include a greater amount of the potentiometer resistance in parallel with one of the equal resistances, and a lesser amount in parallel with the other, the out-

put impedance relative to the line is varied and hence the voltage impressed upon the line is changed, while the total impedance across the output circuit of the oscillator remains substantially constant.

One of the objects of this invention is the provision of means for maintaining the frequency of a carrier source constant under all gain control adjustments. Another object is to provide means for maintaining the constancy of the spacing between the channels of a carrier signaling system.

These objects and others which will be apparent as the nature of the invention is disclosed, may be accomplished in the manner which will be clearly set forth in the following description taken in connection with the attached drawing which shows the invention applied to a carrier telegraph system.

Referring to the drawing, there is shown an oscillator of the type described in United States Patent No. 1,356,763 to R. V. L. Hartley, October 26, 1920. As illustrated, this oscillator comprises an electron discharge device 1 provided with a heated cathode, a control element or grid, and an anode, having an input circuit extending between the cathode and grid, an output circuit connecting the anode and grid, and these circuits coupled in feed-back relation. The coupling connection includes a tuned circuit consisting of an inductance 2 shunted by a condenser 3, either, or both of which may be varied, to determine the frequency of the oscillations generated. Obviously, an oscillator having the tuned frequency determining circuit included in either its input or output circuit may be used as a carrier supply source. The usual filament heating and plate current sources 4 and 5 respectively, and associated control resistances therefore are provided, as are also blocking condensers 6 and a high resistance 7. The blocking condenser 6 shunted by a high grid leak resistance serves in well known manner to maintain the grid of the oscillator at the proper negative potential while the tube 1 is oscillating. Resistance 7 is adapted to minimize the effect of fluctuations in the energy supplied by the battery 5 to the space current circuit of the discharge device 1.

The potential supplied by the oscillator is impressed across the potentiometer resist-

ance or network 8 through the resistance 9. The network 8 comprises resistances 10, 11, 12 and a contact 13 which is adjustably associated with the resistance 10 and is connected through the resistances 11 and 12 with the respective terminals of the resistance 10. The intensity of the electromotive force impressed upon the input circuit of an amplifier 14 may be regulated by adjusting the contact 13 to vary the portions of the resistance 10 connected in parallel with the resistances 11 and 12 respectively. In this manner, while the potential drop across that portion of the resistance associated with the input circuit of the amplifier 14 is varied, the total resistance included in the oscillator output circuit is maintained substantially constant.

Heretofore with the well-known design of potentiometer the resistance of which was of the same order of magnitude as the individual resistances used in the network hereinbefore described, it was found necessary to give the resistance 9 included in the oscillator output circuit, a different value for the different frequency ranges used. For effective transmission over ranges up to 5000 cycles, one value of resistance was used and for ranges between 6000 and 10000 cycles, a resistance five times as great was employed. As the contact of the potentiometer was adjusted to give the necessary "gain," so that signal impulses or trains of oscillations of the required amplitude could be supplied to the line for transmission to a distant receiving station, the frequency of the oscillator varied to such an extent that the spacing between channels was seriously reduced and as a result interference between the different signal channels occurred.

In an effort to eliminate this interference, resort was had to relatively larger channel spacing, but even then, it was found necessary as the potentiometer setting approached the maximum voltage position to readjust the oscillator frequency to its original value in order to secure efficient transmission without interference.

With a potentiometer of the design herein described, signaling may be carried on over all signal channels without change in the value of the resistances included in the oscillator output circuit other than that due to the adjustment of the contact 13. No appreciable change of frequency occurs over the entire frequency range used in carrier telegraph transmission. The frequency of each channel is substantially constant and as a consequence, the several channels may be more closely spaced on the frequency spectrum and hence a larger number of channels are therefore available for signaling purposes than in the circuit arrangements previously used. This arrangement is therefore especially adapted for use in a multi-

plex carrier system, since once the tuned circuits of the oscillators for the respective channels have been set, the desired gain for each channel may be effected by adjusting the potentiometer.

Normally carrier waves are impressed upon the line and signal impulses or trains of oscillations are transmitted to distant receiving station by shunting the oscillating potential normally impressed upon the grid or control element of the amplifier 14 through a path of low impedance for the carrier frequency. A circuit 15, connected across the input circuit of the amplifier 14 and adapted to be controlled by a key, relay or other similar device, is shown for this purpose. Resistance 9 serves to stabilize the operation of the oscillator by preventing changes in the impedance of the load circuit, when the low impedance path 15 is closed during signaling periods, from reacting thereupon. The output circuit of the amplifier includes a tuned circuit comprising the variable condenser 14^a, coils 14^b, and the primary winding of a repeating coil or transformer 17 by means of which the amplifier output circuit is coupled to the line 16. The usual heating and plate sources as well as a blocking condenser and choke coil are associated with the output circuit of the amplifier 14.

A sending circuit including a potentiometer of the type described above, having a resistance 10, provided with twenty-steps, operated between the eighth and thirteenth steps and working into an artificial load circuit of two hundred ohms at twelve thousand cycles gave current of ten milliamperes at the output terminals of the load circuit with the maximum potentiometer setting employed which decreased about one milliampere per potentiometer step. Hence at the midpoint of the resistance 10 the output current was seven milliamperes which is adequate for efficient transmission. It was also found that the frequency change over the entire potentiometer range was not more than ten cycles at any frequency between three thousand and ten thousand cycles. A change of ten volts in the plate battery of the oscillator caused the frequency of the oscillator to vary fifteen cycles. A change of 1 ampere in the heating current for the filament produced a frequency variation of the waves generated by the oscillator of five cycles. In this test the resistance 7 was 24000 ohms and the resistances 9, 10, 11 and 12 were each 100,000 ohms. Hence, while using a constant impedance potentiometer or network of the design hereinbefore described, the necessary adjustments to secure the desired "gain" may be effected without appreciably changing the frequency of the carrier waves impressed upon the line.

While in this description certain specific details have been set forth with the object

of clearly and completely disclosing the various features and method of operation of the invention, it is to be understood that this invention is not limited to these details, but only by the scope of the attached claims.

5 What is claimed is:

1. In combination, a source of oscillations and a transmission circuit connected to said source through a potentiometer which comprises a resistance, an adjustable contact associated therewith, and equal impedance devices connected between the terminals of said resistance and said adjustable contact.

10 2. A source of oscillations, a transmission circuit connected to said source through a potentiometer network comprising a plurality of resistances, a contact adjustably associated with one of said resistances, the other resistances being connected in parallel with said first mentioned resistance, and a connection from the common terminal of said other resistances to said adjustable contact.

15 3. A source of oscillations, a transmission circuit connected to said source through a potentiometer comprising a resistance, an ad-

justable contact associated therewith, and impedances of equal value connected between the terminals of said resistance and said adjustable contact.

4. A source of oscillations, a transmission circuit connected to said source through a potentiometer comprising a resistance, an adjustable contact associated therewith, and a resistance in parallel with said first mentioned resistance having its mid-point connected to said adjustable contact.

30 5. A signal system comprising a source of oscillations, control means for shunting said source, and a potentiometer network connected between said source and said shunting means comprising a resistance, an adjustable contact associated therewith, and a second resistance connected in parallel with said first resistance having its mid-point connected to said adjustable contact.

35 40 45 In witness whereof, I hereunto subscribe my name this 30th day of December, A. D. 1921.

JOHN C. BURKHOLDER.
